United States Patent Office

Des. 224,117
Patented July 4, 1972

224,117

VIDEOTELEPHONE TRANSCEIVER

Donald Michael Genaro, Haworth, and Thomas Joseph Kelly, Middletown, N.J., John Neil McGarvey, Drexel Hill, Pa., and Rembert Ryan Stokes, Middletown, N.J., assignors to Bell Telephone Laboratories, Incorporated, Murray Hill, N.J.

Filed Jan. 7, 1971, Ser. No. 104,830

Term of patent 14 years

Int. Cl. D14—03

U.S. Cl. D26—14

FIG. 1

FIG. 2

FIG. 3

FIG. 1 is a perspective view showing the front and right side of our new design for a videophone transceiver;

FIG. 2 is a side view of the videophone transceiver, the opposite side being substantially a mirror image thereof; and

FIG. 3 is a perspective view showing the rear and left side of the videophone transceiver.

We claim:

The ornamental design for a videophone transceiver, substantially as shown and described.
